DESIGN FOR A CAMERA OR SIMILAR ARTICLE

Otto W. Githens and George Kende, New York, N. Y., assignors to Universal Camera Corporation, New York, N. Y., a corporation of New York

Application March 23, 1936, Serial No. 61,744

Term of patent 14 years

To all whom it may concern:

Be it known that Otto W. Githens and George Kende, citizens of the United States and residents of New York city, in the county of New York and State of New York, have invented a new, original, and ornamental Design for a Camera or Similar Article, of which the following is a specification, reference being had to the accompanying drawing forming part thereof, in which,

Fig. 1 is a side view in elevation of a camera embodying our new design and showing the finder in operative position;

Fig. 2 is a front view in elevation similar to Fig. 1;

Fig. 3 is a plan view in elevation similar to Fig. 1 but showing the finder in inoperative position;

Fig. 4 is another side view in elevation illustrating the opposite side to that shown in Fig. 1, and showing the finder in inoperative position;

Fig. 5 is a rear end view in elevation similar to Fig. 4; and

Fig. 6 is a bottom view in elevation similar to Fig. 4.

We claim:

The ornamental design for a camera or similar article substantially as shown and described.

OTTO W. GITHENS.
GEORGE KENDE.
